WILLIAM RAY INGHRAM, OF TUCSON, ARIZONA; EVA LUSE INGHRAM ADMINISTRATRIX OF SAID WILLIAM RAY INGHRAM, DECEASED.

BINDING-EYELETS.

1,082,335.

Specification of Letters Patent. Patented Dec. 23, 1913.

Application filed November 6, 1912, Serial No. 729,761. Renewed November 15, 1913. Serial No. 801,259.

To all whom it may concern:

Be it known that I, WILLIAM R. INGHRAM, a citizen of the United States, and a resident of Tucson, in the county of Pima and State of Arizona, have made certain new and useful Improvements in Binding-Eyelets of which the following is a specification.

My invention is an improvement in binding eyelets, for securing together in book form a series of periodicals, and has for its object the provision of means whereby the members of the series may be connected together in interlocking relation and in such manner that they may be opened in the same manner as a book.

In the drawings: Figure 1 is a perspective view of a series of periodicals bound together with the improved eyelets; Fig. 2 is an enlarged rear view of the series; Fig. 3 is a perspective view of a part of one cover; Fig. 4 is a similar view of a part of the other cover; Fig. 5 is an end view with the binders in section showing the method of connecting the different members of the series; Fig. 6 is a side view of an eyelet; and, Fig. 7 is a reduced perspective view of the same.

In the present embodiment of the invention two or more eyelets are connected with each of the periodicals to be bound and each periodical is interlocked with the preceding periodical, the covers being interlocked in the same manner as are the periodicals.

In the binding operation a front cover 1 and a rear cover 2 are provided, and the periodicals 3 are arranged between the covers in regular order. Each of the covers 1 and 2 is provided near each of its ends with a clip formed from a plate doubled upon itself to form a U-shaped construction, consisting of an outer member 4, an inner member 5 and a connecting portion 6. The outer member 4 of each clip is provided with an opening 7, and the inner member 5 of each clip is provided with a struck up spur or tongue 8, which is adapted to be passed through an opening in the cover and through the opening 7 of the outer member 4, the point of the spur being bent over upon the outer face of the member 4 to lock the clip in place on the cover.

The clips of the front cover 1 have an opening in the connecting portion 6, as indicated at 9, and an eyelet 10 is arranged at the opening, the said eyelet being formed

from a bar doubled upon itself to form the eye, the ends being bent laterally outward, as shown at 11, and engaging beneath the connecting portion 6 of the clip.

The clips of the cover 2 have a tongue 12 cut from the material of the clip, at the portion 6, and the central portion of the said tongue extends beyond the face of the connecting portion 6, as shown in Fig. 3.

It will be understood that the covers may be suitably ornamented if desired, and may bear the name of the periodical or any other printed matter that may be desired.

Each of the periodicals 3 is provided with a plurality of eyelets, shown more particularly in Figs. 5 to 7 inclusive. Each eyelet is formed from a bar or wire doubled upon itself to form an eye 13, and the ends 14 and 14^a of the wire or bar are then arranged alongside each other, as shown in Fig. 7, and the said ends are pointed in order that they may be easily passed through the material of the periodical. The eye 13 is arranged at approximately a right angle to the ends 14 14^a, the said ends of the wire or bar constituting a shank for the eye.

It will be noted from an inspection of Fig. 7, that one of the ends 14^a is of greater length than the other, so that they may be easily passed through the paper. The said ends are passed through the periodical at its center, from without inward, as shown more particularly in Fig. 5, and the said ends 14 and 14^a are then bent laterally in opposite directions, as indicated in Figs. 2 and 6. While each periodical is shown as provided with two eyelets, it will be understood that as many eyelets may be used as may be desired or found necessary.

As the periodicals are issued, they may be provided with eyelets as above mentioned, and the eyelets of the first periodical are passed through the eyes 10 of the cover before being engaged with the periodical. That is, the ends 14 14^a of each eyelet are passed through the eye 10 or through the eye of the eyelet of the preceding number before the eyelet is engaged with the number. When the next periodical issues, and before it has been provided with eyelets, the said eyelets are passed through the eyelets of the preceding number, and this method of binding is continued until the entire series or volume is completed. After each number is inserted, the cover 2 may be placed, the tongue 12 of the said cover being

passed through the eyelet of the number last inserted. It will be evident that in this manner any number of numbers may be bound together, and the complete book will 5 look as complete with one number in place as it will with a dozen. The eye 13 of each eyelet is as before stated at right angles to the ends 14 and 14^a, and when said ends 14 and 14^a are passed through the periodical, 10 a portion of the said ends adjacent to the eye is left extending beyond the edge of the periodical, as shown at 15, in Figs. 5 and 6. This portion 15 forms a shank for the engagement of the preceding eye. After the 15 numbers are bound together with the covers the eyelets form a chain connecting the covers, and also connecting the periodicals.

When the series of numbers is completed the series may be removed from the covers 20 1—2 and filed away for future reference, and they will remain bound together regardless of whether the covers are in place or not.

To remove a series of periodicals from 25 the covers the cover 2 is first removed by disengaging the snap 12 from the eye of the adjacent periodical. One of the members of the clip may now be released from the cover 1 to permit the disengagement of the 30 eyelet 10. New eyelets may be replaced on the cover 1 and the covers 1 and 2 are then ready for binding. The eyelets 10 are released from the cover 1 by first releasing the clip 5. One arm 11 of the eyelet may 35 then be straightened to permit the said eyelet to be disengaged from the eyelet of the adjacent periodical.

In binding with the improved eyelets, the 40 numbers of the periodicals may be bent freely with respect to each other, as may also the pages of the single periodical.

The eyes 13 of the eyelet are of such size that the eye of the eyelet of the succeeding 45 periodical or number cannot be passed through the eye with which it is engaged, since the eyes of all the eyelets are the same size.

In binding heavy periodicals, it will be necessary to use a moderately stiff wire, and 50 in order to permit the shank to be bent easily and at the proper place, the shank is preferably flattened slightly at the place where it is to be bent, that is, close to the eye, and this feature is shown in Fig. 6. It will be 55 noticed that the angle between the eye and the shank is slightly less than a right angle, this being so arranged to permit the periodical to lie in superposed relation. If the bending were at a right angle, the periodicals would lie in stepped relation.

I claim:

1. In combination with a front and back cover each having a plurality of clips connected with its rear edge, an eye pivoted to 60 each clip of the front cover and mounted to

swing laterally with respect to the plane of the cover, each of the clips of the rear cover having a resilient tongue, and a plurality of binding eyelets for periodicals, each eyelet consisting of an eye and a shank at right angles to each other, said eyelet being formed by bending a wire or bar upon itself to form the eye, the ends of the wire or bar lying alongside each other and one being of greater length than the other, said ends being at right angles to the plane of the eyelet and being adapted to pass through the eye of the succeeding eyelet or the eye of the cover and then through the leaves of the periodical and to be then bent laterally away from each other to hold the eyelet in place.

2. In combination with a front and a back cover, the front cover having a plurality of eyes pivoted to the rear edge thereof and mounted for lateral swinging movement with respect to the plane of the cover, tongues on the rear edge of the rear cover, and binding eyelets each consisting of an eye and a shank at right angles thereto, said shank being split and being adapted to be passed through an eye of the cover or the eye of a preceding eyelet and to engage the periodical to be bound.

3. In combination with a front and a back cover, a plurality of eyes pivoted to the rear edge of the front cover for lateral swinging movement with respect to the front cover, a plurality of tongues on the rear edge of the rear cover, and binding eyelets for the periodicals to be bound, each of the said eyelets consisting of an eye and a shank at right angles thereto, said shank being adapted to pass through an eye of the front cover before engaging the periodical, the tongues of the rear cover being adapted to engage the eyelets of the last periodical in place.

4. In combination with a front and a back cover, the front cover having a plurality of eyes pivoted to the rear edge thereof and mounted for lateral swinging movement with respect to the plane of the cover, tongues on the rear edge of the rear cover, and binding eyelets each consisting of an eye and a shank at right angles thereto, said shank being adapted to pass through an eye of the front cover or an eye of the preceding eyelet and to be afterward secured to a periodical, the tongue of the rear cover engaging the eyelets of the last periodical.

5. In combination, a cover having eyes at its rear edge, and a cover having tongues registering with the eyes, and binding eyelets for the periodicals to be bound, each eyelet comprising a shank for passing through an eye of the preceding periodical or the eye of the cover before engaging the periodical being bound, and an eye for preventing disengagement of the shank, the

tongues of the second cover being adapted to engage the eyes of the last periodical to prevent disengagement thereof.

6. In combination, binding eyelets each comprising an eye and a shank for passing through the eye of an eyelet of the preceding periodical and for then engaging the periodical being bound, the eyes of the eyelets preventing their disengagement, and covers, one cover having eyes for engagement by the shanks of the eyelets of the first periodical, the other cover having spring tongues for engaging the eyelets of the last periodical, said eyes of the eyelets being at an angle to the shanks, the shanks being split and pointed and capable of being bent.

7. In combination, binding eyelets each comprising an eye and a shank for passing through the eye of an eyelet of the preceding periodical and for then engaging the periodical being bound, the eyes of the eyelets preventing their disengagement, and covers, one cover having eyes for engagement by the shanks of the eyelets of the first periodical, the other cover having spring tongues

for engaging the eyelets of the last periodical, said eyes of the eyelets being at an angle to the shanks.

8. In combination, binding eyelets each comprising an eye and a shank for passing through the eye of an eyelet of the preceding periodical and for then engaging the periodical being bound, the eyes of the eyelets preventing their disengagement, and covers, one cover having eyes for engagement by the shanks of the eyelets of the first periodical, the other cover having spring tongues for engaging the eyelets of the last periodical.

9. In combination, binding eyelets each comprising an eye and a shank for passing through the eye of an eyelet of the preceding periodical and for then engaging the periodical being bound, the eyes of the eyelets preventing their disengagement.
